DOOR CHECK DEODORIZING SPRAY

Stanley N. Feldstein, Chicago, Ill.

Application October 29, 1937, Serial No. 171,741

1 Claim. (Cl. 299—82.5)

My invention relates to a door check deodorizing spray for public rooms and the like.

It is well known that public rooms such as wash rooms, lavatories, toilets or the like ordinarily have closed doors because of legal ordinances, sanitary reasons, public appearances, or to prevent embarrassment to persons of different sexes. This closed condition of such rooms makes for foul and obnoxious odors not properly dissipated by the evaporation or drip of deodorants heretofore in use.

Among the objects of my invention are to provide means adapted upon closing the door of such a room to spray the atmosphere in the room so as to properly deodorize and disinfect the same. My device is attachable to any door or door jamb and the spray may be positioned to contact any desired part of the room. My invention comprises such other objects, advantages and capabilities as will later more fully appear and which are inherently possessed by my invention.

While I have shown in the accompanying drawing preferred embodiments of my invention, yet I wish it understood that the same are susceptible of modification and change without departing from the spirit of my invention.

Referring to the drawing, Fig. 1 is a perspective view of my device as used in a room; Fig. 2 is a detail view of the door check; Fig. 3 is a detail view of the atomizer and Fig. 4 is a detail view of the door attachment and resilient means.

Referring to the embodiment selected to illustrate my invention, it comprises a structure 10 adapted to be attached to a door 11 and a door jamb 12. A preferred form of attachment structure 10 includes a pair of spaced bracket arms 14 attached to the door 11 by suitable means such as screws 13 or the like. The inside portion 15 of the arms 14 have serrations 16 to adjustably position a housing 17 held to said arms 14 by bolts 18. A spring arm 19 has its lower end positioned through an opening 20 in the lower portion of the housing 17 and has an extension 21 passing through an opening 23 in the top portion of the housing 17. A resilient member 24 surrounds substantially all of the body portion 25 of the spring arms 19 and extends upwardly to a collar 26 of the spring arm 19. A ratchet wheel 27 is placed around the body portion 25 of the spring arm 19 adjacent the collar 26 so as to engage the top and end of the spring 24 so that upon turning the ratchet the spring may be tightened or loosened. An arm 28 extending from the collar 26 has a pawl 29 to engage the ratchet wheel 27.

A bracket arm 30 is pivotally attached on one

end to bracket 31 attached preferably to the door jamb 12 and on its other end is pivotally attached to the end of arm 28 by suitable means such as bolt 32 and pin 33. Suitably at the middle portion of bracket arm 30 is a flare 34 having an opening 35 adapted to receive the bent outer end 36 of a plunger arm 37 to be held thereto by suitable means such as a pin 38 through hole 39 in the arm 37. The plunger arm moves within compression cylinder 40 and has at its other end a hook and eye 41 holding a plunger 42 to which is attached a leather compression washer 43 inside of which is positioned a spreader cup 44. A vent extends through the wall of the compression cylinder 40 and is preferably located toward the rear thereof and communicates with a tube 46 leading to an atomizer 47. At the rear end of the compression cylinder 40 is another hole 48 with a regulating screw 49 to regulate the checking action for closing the door.

The air supply tube 46 leads to the atomizer 47 which may be placed at any desired position in the room.

The atomizer 47 has a tank 48 to hold a supply of deodorizing and disinfectant material, preferably in a liquid state. The tank 48 has a neck 49 on top of which is an overflow well 50. The air pressure tube 46 leads from the compression cylinder 40 to the removable head 51 of the atomizer 47. Said tube 46 has a vent 52 substantially at right angles to the open end 53 of the liquid tube 54. This construction prevents any flow of liquid into air tube 46 and back into compression cylinder 40.

While I have shown certain forms of attachment means, door check means and atomizer means, yet other forms of these means may be used as within the contemplation of my invention.

Having thus described my invention, I claim:

An atomizer for a door check deodorizing spray comprising an atomizer tank having a supply of deodorizing and disinfectant liquid, a neck extending upwardly from the tank, an overflow well surrounding said neck, an air pressure tube leading from an air compression cylinder through and above the removable head, a liquid exit tube extending upwardly within said tank through said neck and through and above the head and having an opening at its upper end, said air pressure tube extending above said liquid exit tube and having an opening in its inner side wall substantially at right angles to and entirely above the open end of the liquid exit tube so as to prevent any passage of liquid into said air pressure tube and back into said compression cylinder.

STANLEY N. FELDSTEIN.
